UNITED STATES PATENT OFFICE.

AMBROSE E. LYNN, OF DENVER, COLORADO.

AMUSEMENT DEVICE.

Application filed August 6, 1923. Serial No. 655,911.

To all whom it may concern:

Be it known that I, AMBROSE E. LYNN, a citizen of the United States, residing at Denver, the city and county of Denver and 5 State of Colorado, have invented certain new and useful Improvements in Amusement Devices; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to improvements in amusement devices of the type usually referred to as "ocean wave" devices.

It is the object of this invention to produce a device of this type which shall be 20 so constructed that it will operate more satisfactorily and be less subject to wear than devices of this type with which I am familiar.

25 My device, briefly described, consists of three platforms hingedly connected. The central platform is provided at one end with castors or rollers which roll on the upper surface of a horizontal platform. The other end of the central section is fastened 30 to a crank or offset portion of a rotatable shaft and describes a closed, substantially circular, curve when the shaft rotates. The outer ends of the end platforms are also provided with rollers which rest upon inclined platforms. As the shaft is rotated, the end platforms are reciprocated and 35 three outer ends move in oppositely inclined directions, the three platform sections producing a wavelike motion that has given 40 rise to the name "ocean wave."

In order to better and more clearly describe my improvement, I shall have reference to the accompanying drawing in which:

Fig. 1 represents a top plan view of my 45 improved device.

Fig. 2 is a section taken on line 2—2, Fig. 1.

Fig. 3 is a side elevation to a somewhat 50 larger scale of the end of one of the platforms, the view being taken looking in the direction of arrow 3 in Fig. 1.

Fig. 4 is a bottom plan view of the end 55 of one of the end platforms, the view being taken looking in the direction of arrow 4 in Fig. 3; and

Fig. 5 is a section taken on line 5—5, Fig. 4.

The same reference characters will be used to designate the same parts throughout the several views.

Numerals 1 and 2 represent foundation blocks of concrete or other suitable material to the upper surfaces of which are secured pillow blocks 3 within which is journaled a shaft 4 which has an offset portion 5 cooperatively connected with bearings 6 that are secured to the front end 7 of the central platform section 8. Secured to the under surface of the rear end 9 of section 8 are two or more rollers 10 which rest upon the upper surface of the platform 11. A belt wheel 12 is secured to the end of shaft 4 and is rotated through the medium of the belt 13. It is now apparent that when the shaft 4 is rotated, the bearings 6 70 will be moved in a circle about the axis of the shaft and as the front end 7 of the platform is moved in a closed curve by means of the rotating shaft, the rear end will move back and forth, being supported 75 from the platform 11 by rollers 10. Secured by means of hinges 14 to the front and rear ends of platform section 8 are sections 15 and 16, respectively. The free ends of sections 15 and 16 project onto the inclined platforms 17 and 18 which both incline 80 downwardly towards section 8. Secured to the under surface of each free end of section 15 and 16 is a roller assembly 19 (shown in section in Fig. 5, and in the bottom plan 85 view in Fig. 4). The roller assembly consists of a block 20 of wood or other suitable material of a plano-convex, transverse section (Fig. 5) which is secured to the bottom of the free ends of platform sections 15 90 and 16 in the manner shown in Fig. 3. In the lower or convex side of blocks 20 are a plurality of spaced cavities 21, within each of which is mounted a roller 22. The axis of the several rollers coincide and are at 95 right angles to the longitudinal axis of the platforms. The rollers 22 may be made in any desired manner, but are preferably mounted in a casing 23 which has a curved outer surface 24 that is countersunk in 100 block 20 and secured thereto by means of screws 25. The portion of the bottom of platforms 15 and 16, to which the roller assembly is secured, are inclined with respect to the plane of the platforms, in the 105 110

manner indicated most clearly in Fig. 3, so that the rollers will always contact with the inclined surfaces of the platforms 17 and 18 in every position of the platforms 5 15 and 16.

Let us now suppose that the shaft 4 is rotated in a counter-clockwise direction (Fig. 2), platform sections 8, 15 and 16 will then move toward the left. The lefthand 10 end of the section 15 will move upwardly along the surface of the platform 17, while the righthand end moves in the arc of a circle about an axis parallel to shaft 4. The righthand end of platform 16 moves to the 15 left and downwardly along the inclined surface of platform 18, while the lefthand end travels back and forth in a slightly curved line, owing to its attachment by 20 means of hinges 14 to the righthand end of platform section 8. The composite movement of the platform sections causes the upper surfaces to have a peculiar wavelike motion which gives a sensation similar to what 25 would be experienced if one were riding on the ocean waves.

I want to call particular attention to the roller assemblies 19 which are secured to the free ends of platforms 15 and 16. The employment of rollers at this point overcomes the friction that would otherwise be encountered here were sliding surfaces employed. Besides this, the fact that the pivot point of the platforms 15 and 16 are at a 30 considerable distance from the surface of the platforms, modifies the movement to a considerable degree from what it would be if the ends of the platform were in contact with the platforms 17 and 18. I also desire to call particular attention to the particular 35 cross-sectional shape of block 20, as this is essential for successful operation. The plane surface is adapted to be secured to the flat-inclined under surface of the platforms and the convex under-surface permits 40

the blocks and platforms to oscillate about 45 the point of contact of the rollers 22 with the platform surface without the block coming in contact therewith.

Having now described my invention, what I claim as new is:

1. In combination a horizontal surface, a shaft rotatably mounted and spaced from said surface, said shaft having an offset portion, a platform having one end secured to the offset portion of the shaft and the other end slidably connected to the horizontal surface, two opposite inwardly and downwardly inclined platforms spaced from the ends of said first-named platform, a platform section hingedly connected to each end of the first-named platform section and having their free ends supported by the surfaces of the two oppositely inclined platforms and anti-friction means between the free ends of said platform sections and the inclined platforms.

2. In combination a stationary horizontal surface, a shaft rotatably mounted at a distance from the stationary surface with its axis substantially coincident with the plane 70 of said surface, said shaft having an offset portion forming a crank, a platform section having one end rotatably secured to said crank and the other end slidably supported on said horizontal surface, a pair of inwardly and downwardly inclined platforms, one spaced a short distance from the horizontal surface and the other spaced a short distance from the shaft, a platform section hinged to each end of said first-named platform section, each of said second-named platform sections having their free end supported on one of said inclined platforms, and an anti-friction roller-bearing between each of said free ends and the cooperating inclined platform.

In testimony whereof I affix my signature.

AMBROSE E. LYNN
